UNITED STATES PATENT OFFICE.

RAYMOND H. CRAMER, OF NEWARK, NEW JERSEY, ASSIGNOR TO GENERAL MOTORS CORPORATION, OF DETROIT, MICHIGAN, A CORPORATION OF DELAWARE.

FEEDING MECHANISM.

Application filed November 17, 1925. Serial No. 69,614.

This invention relates to feeding mechanism and comprises all the features of novelty herein disclosed, by way of example, as embodied in mechanism for feeding short 5 cylinders or similar articles from a hopper.

When articles, such as cylinders, are placed in a hopper to be delivered through a feed pipe, they are very likely to jam at the entrance to the feed pipe and it is a matter 10 of some difficulty to make them enter the pipe endwise without frequent delays or breaks in the continuity of the stream of articles. This is particularly the case when the length of the articles is approximately 15 the same as, or not much greater than, their diameter. An object of the invention, therefore, is to provide improved mechanism for feeding articles in a stream. Another object is to provide simple and efficient mechanism 20 of this character for rapidly feeding articles endwise in a continuous and uninterrupted stream from a source of supply.

To these ends and also to improve generally upon devices of the character indicated 25 my invention consists in the various matters hereinafter described and claimed.

In the drawings, Figure 1 is a central section.

Figure 2 is a side elevation and 30 Figures 3 and 4 are perspective views of details.

The numeral 10 indicates a supporting bracket which may be bolted in any convenient location on or near a machine for 35 treating the articles, such as a gauging machine. The upper end of the bracket is enlarged at 12 to provide a semi-cylindrical opening mating with a similar opening in a horizontal bracket 14. The two brackets are 40 secured together by clamping bolts 16 which rigidly hold a bushing 18 having a circular flange 20 resting on the top of the brackets. Screws 22 secure the bushing to a long vertical sleeve 24 and to a short delivery tube 45 section 26 which forms a portion of the article guide through which articles pass from a hopper 28. The hopper is herein shown as conical with its side walls converging at a bottom opening to allow the articles to feed downwardly by gravity. The hopper has a depending annular flange 30 by which it is secured by means of screws 32 to the upper end of the long sleeve 24.

The short delivery tube section 26 is spaced 55 away from the hopper and has a pair of op-

posite slots 34 cut in its upper end thereby leaving opposite side extensions 36. In axial alignment with the short tube section 26 is an upper movable tube section of the same internal diameter and herein shown as made 60 in two complementary, segmental sections 38 and 40 which slidably engage one another at opposite sides along the line 42. Sections 38 and 40 have depending spaced extensions 44 and 46, respectively, arranged to enter the slots 34 when said sections are alternately moved to their lowermost positions. Extensions 36 then enter opposite slots formed by the spaced extensions 44 and 46. Thus an interfitting connection is provided 65 between the upper and lower tube sections which leaves a substantially continuous article guide or tube. The sections 38 and 40 are simultaneously slid in opposite directions within the sleeve 24 and their upper 70 ends alternately enter the opening in the hopper to agitate the articles. The ends of the sections are rounded as indicated at 47 and an article A which gravitates to the position shown in Figure 1 is tilted by the 75 oppositely moving sections into a position such that it freely enters the article guide endwise. When one section is raised, the articles slide down over the upper edge of the other section and so on alternately. In some cases, the upper tube section may be made as 80 a single integral tube but the illustrated form is more efficient in rocking the articles 85 to a straight up and down position.

For reciprocating the upper tube section 90 or sections, the following mechanism is provided. Headed screws 48 pass through opposite slots 50 in the sleeve 24 and are fixed to the tube sections. Between the head of each screw and a spacing collar 52 guided 95 in each slot is interposed an antifriction roller 54 arranged to bear against and form a follower for a cam 56 on a cam member 58 which is rotatably mounted around the sleeve 24. The cam is so formed that it 100 raises one section while lowering the other. To prevent the sections from sticking in a raised position, they are pulled downwardly by coil springs 60 attached to studs 62 on sleeve 24 and to studs 64 on the sections, the last mentioned studs passing through guide slots 66 in sleeve 24. The cam member 58 is continuously rotated by a pulley 68 driven by a belt 70 which passes around idler pulleys 72 on bracket 14 to a source of power. 110

The delivery tube section 26 has an annular recess 74 in which a pipe 76 is set to conduct the articles to the desired point for treatment.

5 Although the machine has been described by reference to a specific construction, it should be understood that the invention, in its broader aspects, is not necessarily limited to the form selected for mere illustrative 10 purposes.

I claim:

1. In apparatus of the character described, a hopper having side walls and an exit opening, a delivery tube section spaced from the 15 exit opening, a movable tube section of the same internal diameter as the delivery tube section and interposed between said delivery tube section and the hopper, and means for reciprocating said movable tube section 20 through the opening in the hopper to deliver articles therefrom; substantially as described.

2. In apparatus of the character described, a hopper having side walls and an exit opening, a delivery tube section spaced from said 25 opening, a movable tube section in axial alignment with the delivery tube section and having interfitting connection with the latter, said movable tube section extending through 30 said opening, and means for reciprocating said movable tube section to feed articles from the hopper; substantially as described.

3. In apparatus of the character described, a hopper having side walls and an exit opening, a delivery tube section spaced from said 35 opening, a movable tube section in axial alignment with the delivery tube section, said tube sections having extensions fitting 40 slots in one another to present a substantially continuous guide for articles, and means for reciprocating said movable tube section to feed articles from the hopper; substantially as described.

4. In apparatus of the character described, a hopper having side walls and an exit opening, a plurality of segmental tube sections 45 slidably through the opening in the hopper and forming an exit passage, and means for reciprocating said sections; substantially as described.

5. In apparatus of the character described, a hopper having side walls and an exit opening, a pair of complementary tube sections 55 slidably engaging one another and passing through the opening in the hopper, and means for moving the sections simultaneously in opposite directions; substantially as described.

6. In apparatus of the character described, a hopper having side walls and an exit opening, a delivery tube section spaced from the 60 exit opening, a plurality of tube sections movable through the opening in the hopper, said movable tube sections having extensions in-

terfitting with the delivery tube section, and 65 means for reciprocating the movable sections; substantially as described.

7. In apparatus of the character described, a hopper having side walls and an exit opening, a guide sleeve supporting the hopper, 70 a tube section fixed to the guide sleeve, and a movable tube section slidable in the sleeve in alignment with the fixed tube section; substantially as described.

8. In apparatus of the character described, 75 a hopper having side walls and an exit opening, a guide sleeve supporting the hopper, a tube section fixed to the guide sleeve, a movable tube section slidable in the sleeve, a member rotatable around the guide sleeve, 80 and actuating connections from the member to the movable tube section to actuate the latter; substantially as described.

9. In apparatus of the character described, 85 a hopper having side walls and an exit opening, a guide sleeve supporting the hopper, a tube section fixed to the guide sleeve, a movable tube section slidable in the sleeve, a cam member rotatable around the guide sleeve, 90 and a follower engaging said cam member and connected to the movable tube section to reciprocate the latter; substantially as described.

10. In apparatus of the character described, 95 a hopper having side walls and an exit opening, a guide sleeve supporting the hopper, a tube section fixed to the guide sleeve, a pair of complementary tube sections slidable in the sleeve, a cam member rotatable around the guide sleeve, cam followers engaging said cam member and individually connected to the movable tube sections, said cam followers being oppositely arranged to slide said sections in opposite directions; substantially 100 as described.

11. In apparatus of the character described, 105 a hopper having converging side walls and a bottom opening, a pair of complementary and segmental article guiding members communicating with the opening, and means 110 for causing a relative movement of said guiding members; substantially as described.

12. In apparatus of the character described, 115 a container for articles, and means for delivering articles from the container in a stream, comprising a delivery tube section having slots with an intervening extension, a movable tube section arranged in axial alignment with the fixed tube section and having extensions with an intervening slot, 120 the extensions of the two sections slidably fitting one another to form a substantially continuous article guide; substantially as described.

In testimony whereof I hereunto affix my 125 signature.

RAYMOND H. CRAMER.
